[57] **ABSTRACT**

A rotary magnetic position indicator for displaying 10 discrete indicia in response to a one or two of five

code or a one of five reverse polarity code. A stator core has a yoke with 10 equally spaced, inwardly extending teeth having inner ends defining a bore. A permanent magnet rotor member is rotatably mounted in the bore and has oppositely polarized diametrically opposite ends each spanning the inner ends of three stator teeth and forming air gaps therewith. Five identical field windings are provided each having first and second ends and each comprising first and second coils on the yoke, there being one coil between each different pair of teeth and the two coils of each different winding having a different group of three teeth therebetween. The first end of each different winding is connected to a different external terminal and the second ends of all the windings are connected to a common terminal. The windings are arranged so that upon connection of each different one of the external terminals and the common terminal to a source of direct current, a different group of three adjacent teeth are excited with one polarity, and so that upon connection of the external terminals respectively connected to each different pair of adjacent windings and the common terminal to the source, a different group of five adjacent teeth are excited with one polarity with the middle one of the group of five teeth having a higher magnetic flux density therein than the remaining projections of the group.

ONE OR TWO OF FIVE CODE ROTARY MAGNETIC POSITION INDICATOR

BACKGROUND OF THE INVENTION

1. Field of the Invention

This invention relates generally to rotary magnetic position indicators, and more particularly to rotary magnet position indicators of the type which respond to a one or two of five code or a one of five reverse polarity code.

2. Description of the Prior Art

Rotary magnetic position indicators are commonly employed for displaying discrete indicia in response to the characters of a prearranged code. A common type of such indicator comprises a diametrically polarized permanent magnet rotor and a stator structure having selective energizable field windings thereon, the rotor carrying a drum having the indicia displayed on its surface. Selective energization of the field windings causes the magnetic axis of the rotor to align itself with the respective poles of the field structure which are energized, thereby to provide the desired rotational indication.

A common form of rotary magnet position indicator for displaying 10 discrete indicia, such as the numerals 0 to 9, is provided with five field windings respectively connected to five external terminals and a common terminal and responding to a one or two of five code or a one of five reverse polarity code. In the case of a one or two of five code, energization of each different one of the five windings provides five of the rotational positions and energization of different pairs of the windings provides the remaining five positions. In a one of five reverse polarity code, energization of each different one of five windings with current flow in one direction provides five of the rotational positions and energization of each different one of the windings with current flow in the reverse direction provides the remaining five positions. There are also instances where it is desired to provide a rotary magnetic position indicator displaying some other even number of discrete indicia, such as 12, in response to a similar code, i.e., a one or two six code or a one of six reverse polarity code.

Prior rotary magnetic position indicators responding to a one or two of five code are shown for example in IBM Technical Disclosure Bulletin, Volume 2, No. 2, August, 1959, Page 7, and in U.S. Pats. No. 3,441,927 to J.A. Watkins, No. 3,376,569 to J.A. Watkins, No. 3,350,079 to L.C. Pursiano et al. and No. 3,311,911 to L.C. Pursiano et al. U.S. Pat. No. 3,416,015 to A.F. Ordas and assigned to the assignee of the present application discloses a rotary magnetic position indicator wherein 180° rotation of the rotor member is assured by angularly offsetting the magnetic axis from the geometric axis of the rotor.

SUMMARY OF THE INVENTION

The invention, in its broader aspects, provides a rotary magnetic position indicator for displaying a predetermined even number of discrete indicia, the indicator comprising a magnetic stator core structure having a yoke portion with the same even number of polar projections extending radially inwardly therefrom, the projections being equally angularly spaced around the yoke portion and having radially inner ends defining a bore. A magnetized rotor member is mounted in the bore for rotation about an axis concentric therewith

and having oppositely polarized diametrically opposite ends, each of the opposite ends having an angular span generally equal to the angular span of the inner ends of three adjacent stator projections and forming air gaps therewith.

A polarity of substantially identical field windings equal in number to one-half the same even number and each having first and second ends are positioned on the core structure in angularly displaced symmetrical relationship. Each of the windings has its first end connected to a different external terminal adapted to be selectively connected to one side of a source of direct current potential, the second ends of all of the windings being connected to a common terminal adapted to be connected to the other side of the source. The arrangement of the windings is such that upon connection of each different one of the external terminals and the common terminal to the source and energization of the respective winding thereby, a different group of three adjacent projections are excited with one polarity thus causing the rotor member to rotate to align its opposite polarity end with the respective group of three projections, and that upon connection of the external terminals respectively connected to each different pair of adjacent windings and the common terminal to the source and energization of the respective pair of adjacent windings thereby, a different group of five adjacent projections are excited with one polarity with at least the middle one of the group of five projections having a higher magnetic flux density therein than the outer two of the group of five projections thereby causing the rotor member to rotate to align its opposite polarity end with the middle three of the respective group of five projections, thus providing the predetermined even number of discrete magnetic orientations for the rotor member.

It is accordingly an object of the invention to provide an improved rotor magnetic position indicator for displaying a predetermined even number of discrete indicia.

Another object of the invention is to provide an improved rotary magnetic position indicator of the one or two of five, or one of five reverse polarity code type.

A further object of the invention is to provide an improved permanent magnet rotor member for a rotary magnetic position indicator for displaying a predetermined even number of discrete indicia.

The above-mentioned and other features and objects of this invention and the manner of attaining them will become more apparent and the invention itself will be best understood by reference to the following description of an embodiment of the invention taken in conjunction with the accompanying drawings.

BRIEF DESCRIPTION OF THE DRAWINGS

FIG. 1 is a side cross-sectional view showing one embodiment of the invention;

FIG. 2 is a top view, partly in cross-section, showing the stator and rotor assembly of the indicator of FIG. 1, and also schematically showing the field winding coils and connections therebetween and thereto;

FIG. 3 is an enlarged view of the permanent magnet rotor of the embodiment of FIGS. 1 and 2;

FIG. 4A is a chart showing a one or two of five code which may be employed with the embodiment of FIGS. 1 and 2;

FIG. 4B is a chart showing the coils of the embodiment of FIGS. 1 and 2 which are energized in response to the code of FIG. 4A;

FIG. 5 is a chart showing a one of five reverse polarity code which may be employed with the embodiment of FIGS. 1 and 2;

FIG. 6 is a view, similar to FIG. 2, showing a 12 position indicator incorporating the invention;

FIG. 7 is a chart showing a one or two of six code which may be employed with the embodiment of FIG. 6;

FIG. 8 is a schematic diagram showing another embodiment of the invention;

FIG. 9 is a schematic diagram showing a further embodiment of the invention;

FIG. 10 is a schematic diagram showing yet another embodiment of the invention; and

FIG. 11 is a schematic diagram showing a still further embodiment of the invention.

BRIEF DESCRIPTION OF THE DRAWINGS

Referring now to FIGS. 1 through 3 of the drawings, there is shown a rotary magnetic position indicator, generally indicated at 20, for displaying ten discrete indicia, such as the numerals zero through nine, in response to the characters of a one or two of five code such as shown in FIG. 4A, or a one of five reverse polarity code, such as shown in FIG. 5. Indicator 20 comprises base plate 22 which may be a printed circuit board carrying the connections to and between the coils. Shaft 23 has end 27 seated in opening 28 in base plate 22 and has flange 30 adhesively secured thereto. The stator structure of the indicator comprises core 24 formed of suitable magnetic material having yoke portion 25 with 10 radially inwardly extending, equally angularly spaced polar projections or teeth formed thereon respectively identified as 1' through 10'. The polar projections respectively have inner ends 26 mutually defining a bore. Core 24 is supported on base plate 22 by a plurality of insulator supports 32 respectively aligned with projections 1' through 10', insulators 32 being secured to base plate 22 by pins 34 which also serve to connect the ends of the coils to printed circuit conductors carried by base plate 22.

Toroidal coils respectively identified as 1 through 10 are positioned on yoke portion 25 respectively between teeth 1' through 10', as shown in FIG. 2, there being one coil positioned between each adjacent pair of projections. Coils 1 through 10 are substantially identical, i.e., each having substantially the same number of turns, and are wound on yoke portion 25 in the same sense.

In accordance with the invention, respective pairs of coils 1 through 10 are serially connected to form five identical, angularly displaced, symmetrical field windings respectively having first and second ends. One end of each different winding is connected to a different external terminal A through E, and the other ends of all the windings are connected to a common terminal. More particularly, coils 1 and 4 having three adjacent projections 1', 2' and 3' therebetween are connected in series by connection 36-1, end 38-1 of coil 1 being connected to external terminal A and end 40-1 being connected by common connection 42 to the common terminal, coils 1 and 4 thus forming the first winding. Similarly, coils 3 and 6 having projections 3', 4' and 5' therebetween are serially connected by connection

36-2, end 38-2 of coil 3 being connected to external terminal B and end 40-2 of coil 6 being connected to common connection 42, coils 3 and 6 forming the second winding. Coils 5 and 8 having projections 5', 6' and 7' therebetween are serially connected by connection 36-3, end 38-3 of coil 5 being connected to external terminal C and end 40-3 of coil 8 being connected to common connection 42, coils 5 and 8 thus forming the third winding. Coils 7 and 10 having projections 7', 8' and 9' therebetween are serially connected by connection 36-4, end 38-4 of coil 7 being connected to external terminal D and end 40-4 of coil 10 being connected to common connection 42, coils 7 and 10 thus forming the fourth winding. Finally, coils 9 and 2 having projections 9', 10' and 1' therebetween are serially connected by connection 36-5, end 38-5 of coil 9 being connected to external terminal E and end 40-5 of coil 2 being connected to common connection 42, coils 9 and 2 thus forming the fifth winding.

The serially connected pairs of coils which respectively comprise the field windings are so wound and serially connected that upon connection of each different external terminal A through E and the common terminal to a source 44 of direct current, the three adjacent projections between the respective pair of coils are excited with the same polarity. Thus, considering coils 1 and 4 which comprise the first field winding, with external terminal A connected to the positive side of source 44 by the A element of switch 46 and the common terminal connected to the negative side thus energizing coils 1 and 4, the adjacent groups of three projections 1', 2' and 3' between coils 1 and 4 are excited with "North" polarity, all the remaining projections having "South" polarity, as shown in FIG. 2.

Referring additionally to the stator structure shown in FIG. 6 which differs mechanically from the stator structure shown in FIG. 2 only in that twelve projections and coils are provided, it will be seen that when two adjacent windings are energized, a group of five adjacent projections are excited with one polarity, the middle one of the five excited projections having substantially greater magnetic flux density therein than the remaining four projections. Thus, with terminals A and B connected by switch elements A and B of switch 46 to the positive side of source 44 and the common terminal connected to the negative side, coils 1 and 4 comprising the first winding and coils 3 and 6 comprising the second winding are energized thus exciting the group of five adjacent projections 1', 2', 3', 4' and 5' with "North" polarity, the middle projection 3' having substantially higher flux density therein than the remaining projections 1', 2', 4' and 5' by virtue of the fact that energized coils 3 and 4 are positioned on either side of projection 3'.

Permanent magnet rotor member 48 is mounted on hub 50 rotatably supported on shaft 23 by bearings 52 spaced-apart by spacer 54. Drum 56 preferably formed of suitable plastic material and has inner annular flange portion 58 mounted on hub 50 and outer annular flange portion 60 upon which the indicia are displayed. Rotor member 48 is thus mounted for rotation about axis 62 of shaft 23 concentric with the axis of the bore defined by inner ends 26 of stator projections 1' through 10'.

Permanent magnet rotor member 48 has oppositely polarized, diametrically opposite ends 64, 66 respectively having substantially the same angular span 68 as

the angular span of inner ends 26 of three adjacent stator projections. In the 10 position indicator shown in FIGS. 1 through 3, the angular span of inner ends 26 of three adjacent stator projections and angular span 68 of ends 64, 66 of permanent magnet rotor member 48 is 93°. Opposite ends 64, 66 of of rotor member 48 respectively have polar projections 70, 72 formed thereon respectively having the same angular span 74 as the angular span of inner end 26 of one stator projection. In the ten position embodiment shown in FIGS. 1 through 3, the angular span of inner end 26 of one stator projection and the annular span 74 of rotor member projections 70, 72 is 21°. Opposite ends 64, 66 of permanent magnet rotor member 48 further comprise arcuate surface portions 76 respectively extending on opposite sides of projections 70, 72. It will thus be seen that rotor member projections 70, 72 respectively form relatively small air gaps 78 with inner ends 26 of a diametrically opposite pair of stator projections, such as projections 2', 7', and that arcuate surface portions 76 respectively form slightly wider air gaps with inner ends 26 of the remaining ones of two diametrically opposite groups of three adjacent stator projections, such as 1', 3', 6' and 8'. Permanent magnet rotor member 48 has side portions 82 respectively extending between opposite ends 64, 66 which respectively form air gaps 84 with the remaining stator projections intermediate the two diametrically opposite groups of three adjacent projections, such as projections 4', 5', 9' and 10', air gaps 84 being substantially wider than air gaps 78 and 80.

Referring particularly to FIG. 3, permanent magnet rotor member 48 has a geometric axis 86 extending through rotational axis 62 and respectively through the mid points of polar projections 70, 72. Magnetic axis 88 of permanent magnet rotor member 48 also extends through polar projections 70, 72 but is angularly displaced from geometric axis 86 on one side thereof. The train of permanent magnet rotor member 48 is parallel with grain axis 90 which may be angularly displaced from geometric axis 86 on the opposite side thereof from magnetic axis 88, as shown. However, the grain axis may be angularly displaced from the geometric axis 86 on the same side as magnetic axis 88, or may be coincident with the magnetic axis.

Referring again to FIG. 2, it will now be seen that when a pair of serially connected coils comprising one winding are energized thereby exciting the group of three adjacent stator projections therebetween with one polarity, such as the excitation of adjacent stator projections 1', 2' and 3' with "North" polarity in response to energization of coils 1 and 4, permanent magnet rotor member 48 will rotate to align its "South" polarized end 64 with the "North" polarized stator projections 1', 2' and 3', rotor member projection 70 being aligned with stator projection 2'. Similarly, and referring briefly again to FIG. 6, it will be seen that with the coils of two adjacent windings energized thereby exciting a group of five adjacent stator projections with one polarity, such as the excitation of adjacent projections 1', 2', 3', 4', 5' with "North" polarity in response to energization of the serially connected pairs of coils 1 and 4 and 3 and 6, permanent magnet rotor member 48 will rotate to align its "South" polarized end 64 with the middle three stator projections 2', 3', 4', rotor projection 70 being aligned with the middle stator projec-

tion 3' which has the greatest magnetic flux density therein.

It will now be seen that positive lock-in of permanent magnet rotor member 48 at any selected position is provided, any tendency of rotor member 48 to be "bounced" to a different position due to vibration thereby providing a false reading being eliminated.

Referring now additionally to FIGS. 4A and B, it will be seen that the desired one or two of five code is provided with the common terminal at all times connected to the negative side of source 44 and the five switch elements A through E of switch 46 selectively actuated to connect either one only of the external terminals to the positive side of source 44 thereby energizing the respective pair of serially connected coils, or to connect the external terminals respectively connected to two adjacent windings to the positive side of source 44 thereby energizing the respective two pairs of coils. Thus, as shown in FIGS. 4A and B, with external terminal A and the common terminal respectively connected to the positive and negative sides of source 44 by element A of switch 46, serially connected coils 1 and 4 are energized thereby providing a "zero" reading, and with external terminals A and B connected to the positive side and the common terminal connected to the negative side of source 44 by switch elements A and B of switch 46, coils 1 and 4, and 3 and 6 are energized thereby causing rotor member 48 to rotate to provide a "one" reading.

Referring further to FIG. 5, it will be seen that a one of five reverse polarity code can also be provided by appropriate modification of switch 46. Thus, with terminal A and the common terminal respectively connected to the positive and negative sides of source 44, rotor member 48 is rotated to provide a "zero" reading, and with terminal A and the common terminal respectively connected to the negative and positive sides of source 44, rotor member 48 is rotated to provide a "five" reading.

While a simple, five position manually actuated switch 46 is schematically shown in FIG. 2, it will be readily understood that a solid state switching system may be employed.

Referring now to FIG. 6 in which like elements are indicated by like reference numerals, it will readily be seen that a one or two of six code or one of six reverse polarity code indicator may be provided utilizing the same winding arrangement as shown in connection with the one or two of five code or one of five reverse polarity code embodiment of the previous figures. Here, stator core structure 24 is provided with 12 equally angularly spaced projections 1' through 12' and six angularly displaced, symmetrical windings respectively having ends 38-1 through 38-6 connected to external terminals A through F and ends 40-1 through 40-6 connected to the common terminal. Again, each of the six field windings comprises two serially connected coils having a group of three adjacent stator projections therebetween, there being one only coil 1 through 12 between each pair of stator projections 1' through 12'. Thus, coils 1 and 4 having adjacent projections 1' through 3' therbetween are serially connected between external terminal A and the common terminal, coils 3 and 6 having stator projections 3', 4' and 5' therbetween are serially connected between terminal B and the common terminal, coils 5 and 8 having projections 4', 6' and 7' therbetween are serially

connected between terminal C and the common terminal, coils 7 and 10 having projections 7', 8' and 9' therebetween are serially connected between terminal D and the common terminal, coils 9 and 12 having projections 9', 10' and 11' therebetween are serially connected between terminal E and the common terminal, and coils 11 and 2 having projections 11', 12' and 1' therebetween are serially connected between terminal E and the common terminal.

Referring briefly again to FIGS. 2 and 3, side portions 82 of permanent magnet rotor member 48 are there shown as being formed of two straight segments 81a, 82b respectively disposed at an angle to geometric axis 86, that angle being 15° in the illustrated embodiment. In FIG. 6, side portions 82' of permanent magnet rotor member 48 are shown as being respectively straight between opposite ends 64, 66. The magnet configuration of either FIGS. 2 and 3, or FIG. 6 may be employed in any embodiment of the invention.

Referring briefly to FIG. 7, a one or two of six code is shown for the 12 position indicator 92 of FIG. 6. Thus, to provide a "ten" reading, external terminal F and the common terminal are respectively connected to the positive and negative sides of source 44 thereby energizing serially connected coils 11 and 2 to excite the group of three adjacent stator projections 11', 12' and 1' with "North" polarity thus causing rotor member 48 to rotate to align its "South" end 64 with the three "North" polarized stator projections 11', 12' and 1', rotor projection 70 being aligned with stator projection 12'. Similarly, to provide an "eleven" reading, terminals A and F are connected to the positive side of source 44 and the common terminal to the negative side thus energizing serially connecting coils 11 and 2 and 1 and 4 so as to excite the group of five adjacent projections 11', 12', 1', 2' and 3' with "North" polarity, the middle projection 1' having substantially higher magnetic flux density therein than the remaining four projections 11', 12', 2' and 3', thus causing permanent magnet rotor member 48 to rotate to align its "South" end 64 with the middle three projections 12', 1', 2', rotor projection 70 being aligned with the middle stator projection 1'. It will also be readily seen that a one of six reverse polarity code may be provided by appropriate modification of switch 46.

Referring now to FIG. 8 in which like elements are indicated by like reference numerals, here a 10 position indicator 94 is shown in which each of the five field windings comprises three coils 96, 98 and 100 respectively positioned on an adjacent group of three stator projections, ends 38 of the field windings being respectively connected to external terminals A through E and ends 40 being connected by common connection 42 to the common terminal. Further, in this embodiment, the middle coil 98 of each winding has substantially twice the number of turns as the two end coils 96, 100. Thus, considering the field winding connected to external terminal A, coil 96-1 is positioned on stator projection 1', coil 98-1 is positioned on projection 2', and coil 100-1 is positioned on projection 3', coil 98-1 having substantially twice the number of turns as coils 96-1 and 100-1. It will further be seen that the alternate projections 2', 4', 6', 8' and 10' have only coils 98-1, 98-2, 98-3, 98-4 and 98-5 thereon, whereas each of the intervening projections 1', 3', 5', 7' and 9' respectively have one coil 96 and one coil 100 thereon. It will be understood that permanent magnet rotor member 48 of

the previous figures is rotatably mounted in the bore defined by inner ends 26 of teeth 1' through 10'.

Considering now the first field winding comprising coils 96-1, 98-1 and 100-1, with terminal A connected to one side of source 44 and the common terminal connected to the other side, coils 96-1, 98-1, and 100-1 will be energized thereby exciting the group of adjacent projections 1', 2' and 3' with one polarity, such as "North." In this embodiment, since windings 98 have substantially twice the number of turns as windings 96 and 100, projection 2' will have a magnetic flux density therein substantially twice the magnet flux density in projections 1' and 3'. Permanent magnet rotor member 48 will thus rotate to align its "South" end 64 with the "North" polarized projection 1', 2' and 3', rotor member projection 70 being aligned with stator projections 2'.

Considering now connection of external terminals A and B respectively connected to two adjacent field windings to one side of source 44 with the common terminal connected to the other side, serially connected coils 96-1, 98-1 and 100-1 comprising the first field winding and serially connected coils 96-2, 98-2 and 100-2 comprising the second field winding will be energized thus exciting the group of five adjacent stator projections 1', 2', 3', 4' and 5' with one polarity, such as "North." Here, with both coils 96-2 and 100-1 on stator projection 3' energized, it will be seen that the middle three projections 2', 3' and 4' will respectively have substantially the same magnetic flux density therein whereas, the outer two projections 1' and 5' respectively having only coils 96-1 and 100-2 thereon energized will have a magnetic flux density therein substantially one-half the magnet flux density in the middle three projections 2', 3' and 4'. Permanent magnet rotor member 48 will thus rotate to align its "South" end 64 with the middle three projections 2', 3' and 4', rotor projection 70 being aligned with stator projection 3'.

It will readily be seen that the embodiment of FIG. 8 may also be employed with a one of five reverse polarity code. It will further be seen that with the addition of two stator projections making a total of 12 and one additional field winding comprising three serially connected coils 96, 98, 100, a 12 position indicator may be provided responding to a one or two of six code or one of six reverse polarity code.

Referring now to FIG. 9 in which like elements are still indicated by like reference numerals here, each field winding comprises a first section having three serially connected coils 102-1, 104-1 and 106-1 respectively positioned on a first group of three adjacent stator projections, and a second section also comprising three serially connected coils 108-1, 110-1 and 112-1 respectively positioned on a second group of stator adjacent projections diametrically opposite the first group, the first and second winding sections being serially connected. Again, ends 38 of the field winding sections are respectively connected to external terminals A through E and ends 40 are connected to common connection 42 and the common terminal.

Considering the first field winding, the first section comprises serially connected coils 102-1, 104-1 and 106-1 respectively positioned on adjacent stator projections 1', 2' and 3', end 38-1 connecting external terminal A to coil 102-1. The second section comprises serially connected coils 108-1, 110-1 and 112-1 respectively positioned on adjacent stator projections 6',

7' and 8' which are respectively diametrically opposite projections 1', 2' and 3'. Coil 106-1 of the first section is serially connected to coil 112-1 of the second section by connection 114-1 and end 40-1 connects coil 108-1 to common connection 42. In this embodiment, each of the coils 102 through 112 has substantially the same number of turns and is wound in the same sense on the respective stator projection. It will now be seen that each stator projection has one coil of three different windings thereon. Thus, projection 1' has coil 102-1 of the first section of the first winding, coil 110-3 of the second section of the third winding and coil 106-5 of the first section of the fifth winding thereon, projection 2' has coil 108-4 of the second section of the fourth winding, coil 104-1 of the first section of the first winding and coil 112-3 of the second section of the third winding thereon, and projection 3' has coil 102-2 of the first section of the second winding, coil 110-4 of the second section of the fourth winding, and coil 106-1 of the first section of the first winding thereon.

Assuming now that terminal A and the common terminal are respectively connected to the opposite sides of source 44, serially connected coils 102-1, 104-1, 106-1, 108-1, 110-1 and 112-1 will be energized, first section coils 102-1, 104-1 and 106-1 exciting stator projections 1', 2' and 3' with one polarity, such as "North," and second section coils 108-1, 110-1 and 112-1 exciting projections 6', 7' and 8' with the opposite polarity, such as "South," the remaining projections 4', 5', 9' and 10' being essentially neutral (with rotor member 48 rotatably positioned in the bore defined by inner ends 26 of projections 1' through 10'). Thus, permanent magnet rotor member 48 will rotate to align its "South" end 64 with the "North" polarized stator projections 1', 2' and 3', "North" end 66 of rotor member 48 being aligned with the "South" polarized projections 6', 7' and 8'. Assuming now that external terminals A and B respectively connected to two adjacent windings are connected to one side of source 44 with the common terminal connected to the other side, once again coils 102-1, 104-1, 106-1, 108-1, 110-1 and 112-1 serially connected with external terminal A will be energized, and coils 102-2, 104-2, 106-2, 108-2, 110-2 and 112-2 serially connected to external terminal B are energized. Thus, a first group of five adjacent projections 1', 2', 3', 4' and 5' are excited with one polarity, such as "North" and the remaining group of five projections 6', 7', 8', 9' and 10' are excited with the opposite polarity, such as "South."

With this connection, it will be observed that with external terminals A and B energized, one coil only is energized on projections 1', 2', 4', 5', 6', 7', 9' and 10', i.e., coils 102-1, 104-1, 104-2, 106-2, 108-1, 110-1, 110-2 and 112-2, respectively, whereas two coils are energized on opposite projections 3' and 8', i.e., coils 102-2, 106-1, 108-2 and 112-1, respectively. Thus, the opposite middle projections 3', 8' of the two groups of five adjacent projections have a magnetic flux density therein substantially twice the magnetic flux density in the remaining projections. Permanent magnet rotor member 48 will thus rotate to align its "South" end 64 with projections 2', 3' and 4', its "North" end 66 being aligned with projections 7', 8' and 9', rotor projections 70, 72 being respectively aligned with stator projections 3', 8'.

It will be seen that the embodiment of FIG. 9 may also be employed with a one of five reverse polarity code however, the geometry is such that the embodiment of FIG. 9 can be employed only in indicators where one-half the even number of positions and polar projections is an odd number. Thus, the embodiment of FIG. 9 cannot be employed in a twelve position indicator.

Referring now to FIG. 10 in which like elements are again indicated by like reference numerals, while the embodiment of the invention shown in FIGS. 2 and 6 employs windings formed of toroidal coils and the embodiments of FIGS. 8 and 9 employ windings formed of salient coils, there is here shown an embodiment employing distributed windings. Here, each of the five windings comprises a coil 116 spanning a group of three adjacent stator projections, end 38 of each winding again being connected to an external terminal A through E and end 40 being connected to common connection 42. Thus, coil 116-1 comprising the first winding spans projections 1', 2' and 3', coil 116-2 comprising the second winding spans projections 3', 4' and 5', coil 116-3 comprising the third winding spans projections 5', 6' and 7', coil 116-4 comprising the fourth winding spans projections 7', 8' and 9', and coil 116-5 comprising the fifth winding spans projections 9', 10' and 1'. Each of the coils 116 has substantially the same number of turns wound in the same sense. It will be observed that alternate projections 1', 3', 5', 7' and 9' are respectively spanned by two coils, i.e., 116-1 and 116-5, 116-2 and 116-1, 116-3 and 116-2, 116-4 and 116-3, and 116-4 and 116-5, respectively.

Assuming now that external terminal A and the common terminal are connected to the opposite sides of source 44, coil 116-1 will be energized thus exciting the group of three adjacent stator projections 1', 2' and 3' with one polarity, such as "North." Thus, permanent magnet rotor member 48 will rotate to align its "South" end 64 with the group of three "North" polarized projections 1', 2' and 3', rotor projection 70 being aligned with stator projection 2'.

Assuming now that external terminals A and B respectively connected to the two adjacent windings 116-1 and 116-2 are connected to one side of source 44 with the common terminal connected to the other side, coils 116-1 and 116-2 will be energized thus exciting the group of five adjacent stator projections 1', 2', 3', 4' and 5' with one polarity, such as "North." Here it will be observed that since the middle projection 3' of the group of five projections is spanned by both energized coils 116-1 and 116-2, projection 3' will have substantially twice the magnetic flux density therein as the remaining projections 1', 2', 4' and 5'. Thus, permanent magnet rotor member 48 will rotate to align its "South" end 64 with the middle three "North" polarized projections 2', 3' and 4', rotor projections 70 being aligned with stator projection 3' which has the highest magnetic flux density therein.

It will be observed that the arrangement shown in FIG. 10 may also be employed with a one of five reverse polarity code. It will further be observed that the arrangement shown in FIG. 10 may be employed in a twelve position indicator by the mere addition of two stator projections and one additional winding 116.

Referring now to FIG. 11 in which like elements are still indicated by like reference numerals, here each of the field windings comprises two serially connected

coils 118 and 120, each spanning two stator projections of a group of three adjacent projections, the middle projection of the group being spanned by both coils. Each of the coils 118, 120 has the same number of turns and is wound in the same sense.

Assuming now that external terminal A and the common terminal are connected to the opposite sides of source 44, serially connected coils 118-1 and 120-1 comprising the first winding will be energized thus exciting the group of three adjacent stator projections 1', 2' and 3' with one polarity, such as "North," it being observed that since both coils 118-1 and 120-1 span the middle projection 2', that projection will have a magnetic flux density therein substantially twice the magnet flux density in projections 1' and 3'. Thus, permanent magnet rotor member 48 will rotate to align its "South" end 64 with the group of three "North" polarized projections 1', 2' and 3', rotor projection 70 being aligned with stator projection 2'.

Assuming now that terminals A and B respectively connected to the two adjacent field windings are connected to one side of source 44 with the common terminal connected to the other side, serially connected coils 118-1 and 120-1 comprising the first field winding and serially connected coils 118-2 and 120-2 comprising the second field winding are energized thus exciting a group of five adjacent stator projections 1', 2', 3', 4' and 5' with one polarity, such as "North," it being observed that the middle three projections 2', 3' and 4' will each have a magnetic flux density therein substantially twice the magnetic flux density in the outer projections 1' and 5' since each of the middle three projections is spanned by two energized coils whereas the outer two projections are respectively spanned by one only energized coil. Thus, permanent magnet rotor member 48 will rotate to align its "South" end 64 with the middle three "North" polarized projections 2', 3' and 4', rotor projection 70 being aligned with stator projection 3'.

It will be seen that the arrangement shown in FIG. 11 may also be employed with a one of five reverse polarity code. It will further be seen that the arrangement shown in FIG. 11 may be embodied in a 12 position indicator by adding two additional stator projections and one additional field winding comprising two serially connected coils 118, 120.

While there have been described above the principles of this invention in connection with specific apparatus, it is to be clearly understood that this description is made only by way of example and not as a limitation to the scope of the invention.

What is claimed is:

1. A rotary magnetic position indicator for displaying a predetermined even number of discrete indicia, said indicator comprising: a magnetic stator core structure having a yoke portion with said even number of polar projections extending radially inwardly therefrom, said projections being equally angularly spaced around said yoke portion and having radially inner ends defining a bore; a magnetized, geometrically symmetrical rotor member mounted in said bore for rotation about an axis concentric therewith and having two only oppositely polarized diametrically opposite ends, each of said opposite ends having an angular span generally equal to the angular span of said inner ends of three only adjacent projections and forming air gaps therewith; and a plurality of substantially identical field

windings equal in number to one-half said even number and each having first and second ends, said windings being positioned on said core structure in angularly displaced symmetrical relationship, each of said windings

5 having its first end connected to a different external terminal adapted to be selectively connected to one side of a source of direct current potential, said second ends of all of said windings being connected to a common terminal adapted to be connected to the other side of said source; the arrangement of said windings being such that upon connection of each different one of said external terminals and said common terminal to said source and energization of the respective windings thereby, a different group of three adjacent projections are excited with one polarity thereby causing said rotor member to rotate to align the opposite polarity end thereof with the respective group of three projections, and that upon connection of the external terminals respectively connected to each different pair of adjacent windings and said common terminal to said source and energization of the respective pair of adjacent windings thereby, a different group of five adjacent projections are excited with one polarity with at least the middle one of said group of five projections having a higher magnetic flux density therein than the outer two of said group of five projections thereby causing said rotor member to rotate to align the opposite polarity end thereof with the middle three of the respective group of five projections, thereby providing said even number of discrete magnetic orientations for said rotor member.

2. The indicator of claim 1 wherein said rotor member comprises a permanent magnet.

3. The indicator of claim 1 wherein said rotor member has opposite sides respectively extending between said opposite ends, said sides forming the air gaps with said inner ends of the remaining projections, said other air gaps being substantially wider than the air gaps formed by said opposite ends.

4. The indicator of claim 3 wherein each of said opposite ends of said rotor member has a polar projection thereon forming a first air gap with the middle one of the respective three adjacent stator structure projections with surface portions on opposite sides thereof respectively forming second air gaps with the outer two of the respective three adjacent stator structure projections, said second air gaps being wider than said first air gaps.

5. The indicator of claim 4 wherein said rotor member comprises a permanent magnet, said rotor member having a geometric axis extending through the center of said rotor member polar projections, said rotor member having a magnetic axis also extending through said rotor member polar projections and angularly displaced from said geometric axis on one side thereof, said permanent magnet having a grain axis angularly displaced from said geometric axis.

6. The indicator of claim 1 wherein the arrangement of said windings is such that upon connection of the external terminals respectively connected to each different pair of adjacent windings and said common terminal to said source and energization of the respective pair of adjacent windings thereby, the middle one of the respective group of five projections has a higher magnetic flux density therein than the remaining projections of said group of five projections.

7. The indicator of claim 1 wherein each of said windings comprises two coils connected in series.

8. The indicator of claim 7 wherein said coils are positioned on said yoke portion, there being one only coil positioned between each different pair of said projections, the two coils of each different winding having a said different group of three said adjacent projections therebetween and excited thereby.

9. The indicator of claim 1 wherein each of said windings comprises three coils connected in series, the three coils of each different winding being respectively positioned on a said different group of three adjacent projections and respectively exciting the same.

10. The indicator of claim 9 wherein alternate projections respectively have one coil of one winding and one coil of an adjacent winding thereon, said alternate projections respectively being the middle ones of said different groups of five projections.

11. The indicator of claim 10 wherein the middle coil of each winding has twice the number of turns as the two end coils, said end coils being respectively positioned on said alternate projections.

12. The indicator of claim 1 wherein each of said windings comprises a first serially connected group of three coils and a second serially connected group of three coils with said first and second groups being connected in series, each different winding having the three coils of its first group respectively positioned on a said different group of three adjacent projections and respectively exciting the same with one polarity, and having the three coils of its second group respectively positioned on another group of three adjacent projections respectively diametrically opposite said first-named group of projections and respectively exciting the same with the opposite polarity, each said projection having one coil of each of three said groups of coils thereon.

13. The indicator of claim 1 wherein each different one of said windings comprises a coil embracing a said different group of three adjacent projections and exciting the same, alternate projections being embraced by said coils of two adjacent windings and respectively being the middle ones of said different groups of five projections.

14. The indicator of claim 1 wherein each different one of said windings comprises first and second coils

connected in series respectively embracing the two outer and the middle projections of a said different group of three adjacent projections and exciting the same.

5 15. In a rotary magnetic position indicator for displaying a predetermined even number of discrete indicia and including a magnetic stator core structure having a yoke portion with said even number of polar projections extending inwardly therefrom, said projections 10 being equally angularly spaced around said yoke portion and having radially inner ends defining a bore; a magnetized geometrically symmetrical rotor member mounted in said bore for rotation about an axis concentric therewith and having two only oppositely polarized diametrically opposite ends, each of said opposite ends having an angular span generally equal to the angular span of three only adjacent projections and forming air gaps therewith.

16. The indicator of claim 15 wherein said rotor member comprises a permanent magnet.

17. The indicator of claim 15 wherein said rotor member has opposite sides respectively extending between said opposite ends, said sides forming other air gaps with said inner ends of the remaining projections, said other air gaps being substantially wider than the air gaps formed by said opposite ends.

18. The indicator of claim 15 wherein each of said opposite ends of said rotor member has a polar projection thereon forming a first air gap with the middle one of the respective three adjacent stator structure projections with surface portions on opposite sides thereof respectively forming second air gaps with the outer two of the respective three adjacent stator structure projections, said second air gaps being wider than said first air gaps.

19. The indicator of claim 18 wherein said rotor member comprises a permanent magnet, said rotor member having a geometric axis extending through the center of said rotor member polar projections, said rotor member having a magnetic axis also extending through said rotor member polar projections and angularly displaced from said geometric axis on one side thereof, said permanent magnet having a grain axis angularly displaced from said geometric axis.
